TOOTHBRUSH

Isadore Leyden, Shrub Oak, N.Y., assignor to Riviera
Appliance Corp., a corporation of New York

Filed Mar. 15, 1963, Ser. No. 73,982

Term of patent 14 years

(Cl. D9—2)

FIGURE 1 is a front elevational view of a toothbrush showing my new design;

FIGURE 2 is a side elevational view thereof;

FIGURE 3 is a rear elevational view thereof;

FIGURE 4 is a perspective view thereof on a reduced scale;

FIGURE 5 is a top view thereof; and

FIGURE 6 is a bottom view thereof.

The essential features of my design reside in the portions shown in solid lines on the drawing.

I claim:

The ornamental design for a toothbrush, substantially as shown and described.
